UNITED STATES PATENT OFFICE.

CHARLES J. WOODS, OF SYRACUSE, NEW YORK.

REINFORCED FLOOR CONSTRUCTION.

Application filed August 20, 1923. Serial No. 658,394.

To all whom it may concern:

Be it known that I, CHARLES J. Woods, a citizen of the United States, residing at Syracuse, in the county of Onondaga and State of New York, have invented certain new and useful Improvements in Reenforced Floor Constructions, of which the following is a specification.

This invention relates to fire-proof floors, 10 of the class in which concrete and tiles comprise the component parts, and has for its object to reduce the normal weight of the flat floor panels, without sacrificing any of their strength. A further object is to provide an exceptionally strong floor structure 15 of the class, in which is eliminated all unnecessary dead weight of the floor itself, whereby a greater proportion of the strength of the slab, of a given thickness, may be 20 utilized for sustaining the maximum loads the floor is intended to support.

A further object is to provide a floor construction, wherein hollow tiles are disposed in rows in two directions, the said rows being 25 suitably spaced, and the spaces between the tiles being filled with plastic or semi-plastic concrete, for forming lengthwise and crosswise ribs or beams; between which, and the ends and lateral sides of the tiles, there is 30 effected a perfect bond, thereby producing a continuous floor slab of minimum weight and maximum strength. Furthermore, the concrete ribs are directly reenforced by the usual lengthwise and crosswise iron or steel rods, the latter being embedded in the concrete near the bottom plane of the floor 35 and withstanding the usual tension and shear stresses, while the tops of the tiles and ribs, due to the intimate bonding of the 40 parts, effectually resist the bending stresses when the floor is subjected to abnormal loads.

The prime object of the invention is to prevent any of the concrete comprising the ribs or beams from entering the open ends 45 of the tiles. This object is accomplished in a simple manner, by the use of novel closures or stoppers, which may be made out of relatively light gage sheet metal or fibre; the stoppers preferably being flexible and capable of being slightly arched or bent 50 for facilitating their ready and quick application to the open ends of the cells; the said stoppers being thereafter held in place by 55 their own tension, and being so fashioned

and disposed that the end-faces of the tiles are directly exposed to and become readily and intimately bonded with the series of concrete ribs, which close the interstices at 60 the ends of the tiles.

Heretofore, it has been proposed, in the construction of tile-and-concrete floors of the class, to allow more or less of the plastic concrete comprising the intersecting ribs or beams to enter the open ends, and to partially fill the cells of the tiles, thereby forming substantially solid plugs, having for 65 their object to prevent the collapse of the ends of the tiles, when the floor slab is subjected to stresses due to the imposing thereon of abnormal loads. This practice, owing to the great number of the hollow tiles throughout a floor, and the still greater number of the cells in which these concrete plugs 70 are formed, has resulted in greatly increasing the normal dead weight or load of the floor, without producing any very useful results. The concrete comprising the intersecting ribs, owing to its semi-plastic nature, 75 and its entry being controlled by gravity, 80 merely forms an angular plug, which only bonds at the sides and bottoms of the cells, and leaves the tops of the cells empty, and particularly the top walls of the tiles unsupported during the bending and crushing 85 stresses when the floor-slab is in compression.

According to my invention, the intersecting concrete ribs extending in the one direction, intimately and solidly bond with the plain sides of the tiles, so that the sides require no additional reenforcing in order to withstand the compression stresses, for the reason that said stresses invariably are exerted downwardly, instead of laterally. On 90 the other hand, by preventing the entrance of any of the concrete into the open ends of the cells, through the employment of my novel stoppers, which conform to and close the cell-openings, and by exposing the top, 95 bottom and side end-faces of the clay tiles to the wet concrete that comprises the ribs that extend in the transverse direction, I am able to effect such an intimate and strong bonding of the ends of the tiles with the said ribs, as 100 well as with the stoppers, as to obviate all danger of the collapse of the ends of the tiles, whether the slab is in tension or in compression. My construction effects a saving 105 of from fifteen to twenty per cent of dead 110

and useless weight that many of the older floors carry, and having substantially equal strength, my floor will sustain correspondingly greater live or abnormal loads.

- 5 A further and general object is to provide a type of reenforced concrete-and-tile floor construction, wherein the ceilings, throughout the length and breadth of the spans between the girders and columns, are 10 free from depending beams, which ordinarily hinder both plain and ornamental plastering; and wherein the use of steel lath, expanded metal, or common clay tiling, except where such plaster-supporting parts are 15 embedded in the concrete of the intersecting ribs, is obviated, thereby further lessening the normal dead weight of the spans and correspondingly increasing their capacity for sustaining the abnormal or live loads. 20 The present construction entirely eliminates the usual superposed sheet or layer of concrete, which has chiefly been employed for taking care of the compression stresses of the floor, and in lieu thereof, it is proposed 25 to increase the thickness of the top walls of the tiles and cellulate the same, as well as to increase the depth of the tiles and concrete ribs, thereby increasing the resistance to the compression stresses without proportionately increasing the normal dead weight 30 of the floor slabs.

I attain these objects by the means set forth in the detailed description which follows, and as illustrated by the accompanying 35 drawings, in which—

Figure 1 is a broken plan view of a floor panel, showing the two-way arrangement of the tiles, the concrete beams, and reenforcing rods, and the application of the 40 stoppers to the open ends of the blocks. Fig. 2 is a vertical longitudinal section, taken on line 2—2 of Fig. 1. Fig. 3 is an end elevation of one of the tiles, showing the cells closed by plain stoppers disposed 45 horizontally. Fig. 4 and Fig. 5 are similar views, showing the stoppers disposed vertically. Fig. 6 is a broken top plan view of the tile shown in Fig. 3. Fig. 7 is an end view of a tile, showing stoppers 50 having their ends slotted for providing flexible lugs that alternately engage the inner and outer surfaces of the tile. Fig. 8 is a vertical section, taken on line 8—8 of Fig. 7. Fig. 9 is a view showing a one-part stopper for closing the four cells of the tile. Fig. 10 is a vertical section, taken on line 55 10—10 of Fig. 9. Fig. 11 is an end view of a tile having its top portion reenforced by a thickened cellular wall, showing stoppers provided with retaining lugs that engage the small cells at the top, while their plain lower ends engage the larger cells at the bottom of the tile. Fig. 12 is a vertical section, taken on line 12—12 of Fig. 11. Fig. 13 is a plan view of the stopper shown 60 in Figs. 9 and 10. Fig. 14 is a similar view of the stopper shown in Figs. 7 and 8, and Fig. 15 is a view showing the slotted stopper applied like the plain stoppers.

In the drawings, the floor panel or slab (Fig. 1), consists of lengthwise and cross-wise concrete ribs or beams 2—2'; filling blocks 3—3', and metal reenforcing rods 4—4', the said ribs and blocks being arranged flat and of uniform thickness 70 throughout.

The blocks 3—3' are preferably the ordinary cellular baked clay tiles in common use, and having four or more cells 3^a, which extend unobstructed throughout the length 80 of the tiles, the said cells being formed by vertical and horizontal interior walls 3^b—3^c. At the start of the floor construction, a temporary centering or platform (not shown) is erected upon which the tiles are placed 85 in spaced relation in two directions. Before, or at the time the tiles are placed in position, the open ends are preferably closed by closures or stoppers 5 and 5', which preferably consist of flexible sheets of metal 90 of suitable gage. The stoppers 5, for example, are disposed horizontally, and are preferably slightly longer than the distance between the remote inner sides 3^d of the tiles, so as to allow the strips of metal to 95 be slightly bent or arched, in order that their ends may enter the cells and frictionally engage the inner surfaces of the side walls 3^d, while the medial portions of the stoppers extend across and bear against the 100 interior walls 3^b, as best seen in Figs. 1, 2, 3 and 6. When the stoppers are thus applied to the cells, they are held rigidly in place by their own tension. After the tiles have been properly positioned, as described, 105 concrete in plastic or semiplastic state is poured into the interstices between the rows, for forming the ribs 2—2', the concrete usually being tamped so as to compactly fill the spaces. The concrete makes 110 direct contact with the outer surface of the plain sides 3^d, as well as with the end-faces of the tiles, and effects a perfect bonding 115 with the tiles. It will be understood, that in applying the closures 5, the top, sides 120 middle and bottom end-faces of the tiles are preferably exposed to the concrete, so that there is substantially a uniform bonding effected throughout the breadth and depth of the tiles. When the stoppers 5 are employed, the latter substantially cover the vertical walls 3^b, and while there is no direct bonding of the said walls with the concrete, the nature of the stoppers is such 125 that the concrete readily adheres to and bonds with the relatively broad surface of the stoppers, thereby effecting a stronger union than if the medial bonding occurred only at the walls 3^b. The presence of the stoppers, which substantially cover the 130

whole end areas of the tiles (see Fig. 3), results in the formation of a broad and deep concrete abutment, which is intimately united to the tiles and stoppers throughout said area, and the metal of the stoppers being of such nature that it will not fracture when the panel is subjected to compression stresses, and the ends of the stoppers being interlocked with the opposite side walls 3^a, as well as with the horizontal walls 3^c of the tiles, the joints between the ends of the tiles and the concrete ribs possess practically the same strength and resistance as any other part of the panel. The closures 5 (5) effectually prevent any of the concrete from entering the cells of the tiles, and therefore greatly reduce the dead weight of the floor slab, without sacrificing any of its compression-resisting strength, since there is a perfect bond throughout the whole end area of the tiles, as described, and the metal closures being entered into the open ends of the cells, as shown in Figs. 1 and 6, serve to support the horizontal walls of the tiles, 25 in the direction in which the metal has greatest resistance when the panel is in compression.

The reenforcing rods 4—4' are preferably disposed near the bottom plane of the panel, 30 and take care of the tension and shearing stresses, in the usual manner.

The tiles 3' (see Figs. 1, 2 and 4) are fitted with plain closures 5', which are disposed vertically and perform substantially the same functions as the stoppers 5, except that the closures 5' when sprung into place tend to exert their tension vertically, thereby directly supporting the top walls 3^c of the tiles, instead of the lateral walls 3^a. By 40 this slightly modified arrangement of the closures, there is a direct bonding between the concrete 2' and the end-faces of the top, bottom, side and inner vertical walls 3^b, while there is no direct bonding with the inner wall 3^c. The closure 5' being slightly curved vertically, effects a corresponding molding of the concrete, which tends to increase the interlocking of the ribs 2' with the ends of the tiles for resisting the compression stresses.

The closures or stoppers may be made in many shapes and dimensions, to suit the different styles and sizes of tiles, and yet perform substantially the same functions, 55 as, for example, as shown in Figs. 7 and 8, wherein stoppers 5^a are disposed vertically the same as stoppers 5', but the opposite ends of the stoppers 5^a are slotted, for providing flexible lugs 5^b—5^c, which alternately engage the inner and outer faces of the top and bottom walls 3^e—3^f. The lugs 5^c are 60 preferably slightly longer than the lugs 5^b, so that they may slightly overlap the end-faces of the top and bottom walls, as shown, 65 and still leave the greater portion of said

ends exposed to the concrete 2', for effecting the intimate bonding that is desirable. This offsetting of the lugs of the stoppers 5^a, provides a plurality of shallow indentations, or recesses, as at *x* in Figs. 7 and 8 adjacent the walls 3^e—3^f, into which the concrete 2' enters and thereby effects a positive mechanical interlocking of the concrete with the tiles, while at the same time, the stoppers 5^a prevent the concrete from entering the 70 cells, and unnecessarily increasing the normal weight of the slab. After the stoppers are applied as herein shown and described, the ends of the tiles appear slightly convexed, and when the concrete is poured into the spaces between the tiles, the latter become interlocked in a manner to further strengthen the bond or union of the tiles and concrete ribs.

In Figs. 9 and 10 is shown another form 85 of stopper, a relatively large metal plate, comprising similar body portions 5^d which are normally spaced the breadth of the vertical walls 3^b by integral spacers 5^e. Each of the body portions 5^d may be cut away centrally, as at 5^f, for exposing portions of the horizontal walls 3^c, which may bond directly with the concrete 2'.

Figs. 11 and 12 show a tile 6, having four relatively large cells 6', which are formed by vertical and horizontal walls 6^a—6^b, and wherein the top wall 6^c is thickened and formed with a number of relatively small cells 6^d, for stiffening the said wall. This form of tile may be employed when extra heavy loads are to be carried by the floor slab, in lieu of the usual superposed sheet or layer of concrete, heretofore employed for taking the compression stresses. When the tiles 6 form the filler blocks of the slab, the stoppers, as 5^x are preferably formed with a plurality of spaced flexible lugs 5^y, which are bent and sprung into the cells 6^d, while the plain bottom ends of the stoppers are bent and sprung into the bottom cells, the 100 same as stoppers 5^a—5^d.

In Fig. 15 is shown the adaptation of the slotted stoppers 5^a to an ordinary tile, the same as stoppers 5'. From the foregoing it will be understood that although I have 115 shown several differently constructed stoppers, they all serve substantially the same function, and are practically interchangeable when applied to tiles of the same style or make.

Having thus described my invention, what I claim is—

1. In a floor slab, a hollow, open-ended tile, and flexible sheet metal stoppers for closing the open ends of the tile for preventing the concrete from entering the same, the ends of said stoppers being flexed inwardly and inserted in the said open ends and being held in place by the tension of the metal. 125
2. The combination with a tile having a 130

- plurality of cells extending therethrough, and being separated by an interior wall, a stopper for preventing concrete and other matter from entering the cells, said stopper comprising a flexible sheet adapted to span the openings, the ends of the stopper adapted to be flexed and inserted in the remote portions of the openings, the medial portions of the stoppers being sprung over the end face of the interior wall and said stopper adapted to be held from displacement during handling of the tile by the tension of said sheet.
3. A floor slab including a hollow open-ended tile, a flexible sheet metal stopper disposed across the ends of the tile and closing the openings in said end, said stoppers being longer than the span of the alining openings, the ends of said stoppers adapted to be bent for insertion in said openings, and being held against the remote inner walls of the tile by the tension of the metal, and the medial portions of said stoppers convexing outwardly beyond the body lines of the tile.
4. A floor slab including a hollow tile divided by intervening interior walls into cells extending lengthwise and providing corresponding openings at the opposite ends of the tile, and flexible stoppers for closing the open ends adapted to be bent and spring into said openings, the said stoppers being of greater length than the span of the adjacent alining openings and the medial portions of the stoppers abutting and being supported by said intervening
- interior walls and projecting into the spaces between the ends of adjacent tiles.
5. A closure for the open end of a floor tile, comprising a flexible sheet adapted to be sprung into the tile open end by the outward flexing of the medial portion of said sheet, the inwardly directed marginal portion of the sheet being slit to form independent lugs.
6. A hollow, open-ended floor tile having an outwardly convex closure for its open end sprung into said open end by the outward flexing of the medial portion of said closure.
7. A hollow, open-ended floor tile having an outwardly convex closure for its open end supported medially by the tile with its end portions sprung inwardly into engagement with the opposing inner walls of said tile.
8. A hollow, open-ended floor tile having an outwardly convex closure for its open end sprung into said open end by the outward flexing of the medial portion of said closure, the marginal portion of the latter carrying independent, flexible lugs.
9. An open-ended tile having a sheet-like closure sprung into the tile open end, the marginal portion of the closure having independent, flexible lugs spaced to fit between partitions and walls of the tile.

In testimony whereof I affix my signature.

CHARLES J. WOODS.
